United States Patent Office.

J. T. WHEELER, OF ST. CHARLES, ILLINOIS.

Letters Patent No. 77,340, dated April 28, 1868.

IMPROVED WASHING-MACHINE.

The Schedule referred to in these Letters Patent and making part of the same.

TO ALL WHOM IT MAY CONCERN:

Be it known that I, J. T. WHEELER, of St. Charles, in the county of Kane, and State of Illinois, have invented certain new and useful Improvements in Washing-Machines; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to washing-machines, and consists in a certain new and useful improvement in gearing for operating them. In the drawings—

Figure 1 is a perspective view.

Figure 2 is a transverse vertical section on the line x x of fig. 1.

Figure 3 is a view of a part detached and modified, and

Figure 4 is a perspective view of the gearing detached.

In constructing my machine I make a box, A, of any rectangular or other desired form, and of any suitable size, and provide it with a lid or cover, B, hinged at a , and with a hole and plug, b , on line with the bottom, as shown in figs. 1 and 2.

To the top of the cover B, I attach standards or supports, c , and mount thereon a cog-wheel, C, which gears into a pinion, D, placed parallel with the cover B, and rigidly connected with the head of the stirrer E, as shown in figs. 1 and 2.

The head of the stirrer E is arranged to work easily in the cover B, and to be supported by it. The bearings of the stirrer on the upper side of the cover, under the pinion D, I make of metal or any suitable material, and construct them so as to prevent any vertical motion of the stirrer.

The cog-wheel C, I provide with a lever, F, so as to extend radially from its centre, and by which a reciprocating rotation may be given to it, and through it imparted to the pinion D and stirrer E.

The stirrer E, I make in one of two forms, though other forms may be used, if desired. As shown in fig. 1, I cross two pieces, d , at right angles, and attach a pin or stirrer, e , to each, and fasten them to the head which connects it with the gearing, or else I take a single piece, f , and insert pin g in it, as clearly shown in fig. 3. If desired, these and other forms may be used interchangeably.

The gear-wheels C and D stand at right angles to one another, and have their cogs wholly on their peripheries, so as to play into one another at right angles, and are so formed that their lines of contact with each other will be perfect when in operation. The shape of the cogs necessary to secure this result is shown in fig. 4. This gearing I believe to be more efficient for the transmission of power than the bevel-gearing, for the reason that it is more direct.

The pins e of the stirrer E, I make long enough to extend well down into the box A, and set them so that their lower ends will spread out, as shown in fig. 1.

In operating my washing-machine, I place the articles to be washed in the box A, and then close down and fasten, if necessary, the lid B. The pins e of the stirrer E will project down upon and among the articles. The lever F should then be moved rapidly backward and forward, thus giving a reciprocating rotary motion to the wheels C D and stirrer E. By this means the articles are thoroughly washed, and most of the wear and tear caused by the rubbing in many machines is avoided. When sufficiently washed, the lid B can be turned back with the stirrer E attached, and the clothes or other articles removed, and others placed in to undergo a similar operation.

It is obvious that the gear-wheel C may be operated by a crank, or similar means, instead of a lever, F, but from experiment I believe the lever is the most efficient, and therefore prefer it.

Having thus described my invention, what I claim, is—

A washing-machine, consisting of the box A, lever F, gear-wheels C and D, and stirrer E, provided with the spreading-pins e , when constructed and arranged as herein described and for the purpose set forth.

J. T. WHEELER.
